UNITED STATES PATENT OFFICE.

GOTTLIEB BINDER, OF LOUISVILLE, KENTUCKY, ASSIGNOR OF ONE-HALF TO
JOHN BINDER, OF RIVERSIDE, KENTUCKY.

BOLT-CLIPPER.

SPECIFICATION forming part of Letters Patent No. 737,198, dated August 25, 1903.

Application filed September 8, 1902. Serial No. 122,503. (No model.)

To all whom it may concern:

Be it known that I, GOTTLIEB BINDER, a citizen of the United States, residing at Louisville, in the county of Jefferson and State of Kentucky, have invented certain new and useful Improvements in Bolt-Clippers; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to improvements in cutting devices, and more particularly to an improvement in bolt-clippers in which the cutting force is applied by vertical instead of horizontal leverage; and the object of the invention is to provide a most simple, efficient, compact, and durable tool for cutting off the ends of bolts.

To this end the invention essentially consists of a tool having a stationary and a pivoted handle and having its body formed with an opening through which one end of said pivoted handle extends when the tool is opened, said body having a member of the cutting device at its end, remote from the handle and a plunger mounted to reciprocate in said body and having at one end the other cutting member and a spring for moving the plunger in one direction, said plunger and movable handle having contiguous ends, which are curved in reversed directions.

In the drawings, Figure 1 represents a top view of my bolt-clipper when closed with the handles partly cut away. Fig. 2 represents a vertical longitudinal sectional view, on a median line, of my clipper when partly open for the admission of a bolt with handles partly cut away. Fig. 3 is a top view of a modified form of my clipper adapted to receive the end of the bolt to be clipped from the side instead of from the bottom.

In the drawings, A represents the body of my bolt-clipper, rectangular in cross-section and having a rectangular bottom to receive a plunger B, similarly rectangular in cross-section, its inner end B' curved eccentrically to engage the eccentric end C of a handle H, pivoted on a bolt D, journaled in the sides of the

frame A and its outer end bearing a cutting knife b. Against the outer end of the frame A and within it is placed a steel block E, as shown, having a cutting edge e, its edge opposite to and parallel with the edge of the cutting-knife b. In the bottom of the frame A, under the knives when the cutter is closed, is an aperture to admit the end of the bolt to be cut when the bolt-cutter is open for action. 55

F represents a coil-spring, one end of which is fastened to a post J, in the bottom of the plunger B near the end bearing the knife, and the other to a post K in the top of a removable piece G, forming a bottom to part of the frame A. The bottom of the frame A is extended backwardly to form a rigid handle H' and is formed with an opening G', through which the eccentric end C of the handle H projects when the opposite end of said handle is 60 raised. Attention is called to the fact that the engaged ends of the movable handle and plunger are curved in opposite directions and are relatively such as to cause said plunger to be moved through a comparatively great distance with maximum ease and that by forming the body or frame of the tool beneath the eccentric C with an opening through which said eccentric projects when the handle H is raised the device is made most compact in 65 construction. The frame and handles are 70 preferably made of malleable iron. 75

I represents a set-screw in the fixed handle adapted to take up the wear in the knife b.

The operation of my bolt-cutter may be described as follows: When it is desired to cut the end off a bolt, the pivoted handle H is raised until its eccentric end C and handle H take the position indicated by the dotted lines in Fig. 2, the eccentric taking about the 80 position C', when the spring F causes knife-bearing plunger B to follow the eccentric and uncover the aperture in the bottom of A between the cutting edges of the knives. When the bolt end is inserted in the aperture, the 85 handles are grasped by the operator and the handle H is depressed vertically, the knife-bearing plunger B is pressed forward against the bolt, which is pressed against the knife-edge e till severed. It is apparent that a 90 greater leverage can be obtained by the pivoted handle pressing down vertically then by 95 100

pressure exerted horizontally. To cut a bolt so placed that its end cannot be inserted in the aperture in the bottom of the frame, so as to secure vertical leverage on the knives, I provide an aperture M, as shown in Fig. 3, in the side of the frame by which the bolt can be inserted between suitably-arranged knives. In this case the frame should be strengthened by a rib L, extending around the side opposite the aperture M and the end.

Having thus described my invention, what I claim as new, and desire to secure by Letters Patent of the United States, is—

1. A bolt-clipper, comprising a frame having a cutting member at one end and a stationary handle at its other end, and also having an opening adjacent to said handle, and provided between said opening and cutting member with a removable bottom plate; a plunger in said frame, mounted to reciprocate above said removable bottom plate, said plunger having a cutting member at one end and its other end curved, a pivoted handle for pressing the plunger in one direction, said handle having at one end a cam arranged to project through said opening in the frame when the handle is raised, said cam being curved in a direction the reverse of that of the curved end of said plunger and engaging the same, and a spring acting in opposition to said cam and arranged in a space between said removable bottom and the under side of the plunger, substantially as described and for the purposes set forth.
2. A bolt-clipper, comprising a frame having a chamber at one end and a fixed handle at its other end and provided with a removable bottom plate for its said chamber, supporting means above said bottom plate, a plunger mounted to reciprocate in said chamber, on said supporting means and out of contact with said bottom plate, a spring for adjusting said plunger in one direction, said spring being secured to the plunger and frame and located in the space between said plunger and removable bottom plate, a knife carried by said plunger and presented to the knife of said frame, and a pivoted handle having a cam to engage said plunger and adjust the same in opposition to said spring, substantially as shown and described.

the removable bottom plate, a cutting member at one end of said chamber, a cutting member carried by said plunger, and a pivoted handle having a cam to engage said plunger and adjust the same in opposition to said spring.

3. A bolt-clipper, comprising a frame having a cutting member at one end and a stationary handle at its other end, said frame having a strengthening-rib at one side and an aperture at the bottom of its other side, said aperture extending transversely of the frame from a place contiguous to the cutting member thereof, a plunger mounted to reciprocate in said frame and provided with a cutting member at one end, and a pivoted handle engaged with the other end of said plunger and operated to adjust the same.

4. A bolt-clipper, comprising a frame, having a chamber at one end, a fixed handle at its other end and a laterally-extending aperture at the bottom, and provided with a removable bottom plate for its said chamber, supporting means above said bottom plate, a knife at one end of said chamber, contiguous to said aperture, a plunger mounted to reciprocate in said chamber and on said supporting means and out of contact with said bottom plate, a spring for adjusting said plunger in one direction, said spring being secured to the plunger and frame and located in the space between said plunger and removable bottom plate, a knife carried by said plunger and presented to the knife of said frame, and a pivoted handle having a cam to engage said plunger and adjust the same in opposition to said spring, substantially as shown and described.

In testimony whereof I affix my signature in presence of two witnesses.

GOTTLIEB BINDER.
